DESCRIPTION

FIG. 1 is a perspective view showing my new design of a motor;

FIG. 2 is a front view thereof;

FIG. 3 is a top plan view thereof;

FIG. 4 is a bottom plan view thereof;

FIG. 5 is a left side view thereof; and,

FIG. 6 is a right side view thereof.

The rear view of the design is symmetrical to the front view shown in FIG. 2.
